(57) **CLAIM**

The ornamental design for a docking station, as shown and described.

DESCRIPTION

FIG. 1 is a perspective view of a docking station showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a cross-sectional view taken along line 9-9 in FIG. 3;

FIG. 10 is a cross-sectional view taken along line 10-10 in FIG. 3;

FIG. 11 is an enlarged view of the portion, labeled '11' of FIG. 10;

FIG. 12 is a perspective view thereof in an alternate state; and,

FIG. 13 is a perspective view thereof in another alternate state of use.

The broken lines in FIG. 13 showing the additional tablet computer depict environmental structure only and form no part of the claim design. All other broken lines depict portions of the article that form no part of the claimed design.

1 Claim, 11 Drawing Sheets
